UNITED STATES PATENT OFFICE.

FREDERICK CROCKER, OF TITUSVILLE, PENNSYLVANIA.

IMPROVEMENT IN TORPEDOES FOR OIL-WELLS.

Specification forming part of Letters Patent No. 85,730, dated January 12, 1869.

To all whom it may concern:

Be it known that I, FREDERICK CROCKER, of the city of Titusville, county of Crawford, and State of Pennsylvania, have invented certain new and useful Improvements in Torpedoes for Use in Oil and other Artesian Wells; and I do hereby declare that the following is a full, clear, and exact description thereof, reference being had to the accompanying drawings, which form a part of this specification.

In operating oil-wells, it is frequently found advantageous to shatter the oil-bearing rock, so that oil may be drawn from adjacent crevices not originally reached by the drill, using, for this purpose, long cylindrical-shaped shells or torpedoes filled with powder or other explosive material, lowered to the proper depth, and exploded.

Various devices and arrangements are in use for igniting the shell; among others, that of a percussion-cap, placed in the center of the torpedo-cap, and ignited by means of a weight dropped from the top of the well, the flame from the cap igniting a small quantity of powder within a "priming-chamber," and from thence communicating with the powder at the upper end of the shell, or, in many cases, communicating directly with said powder, without the intervention of a priming-chamber.

When the percussion-cap is used a small plunger or hammer is suspended over and almost in contact with it, said hammer receiving the blow from the falling weight and imparting it to the cap, and a rubber packing is necessarily wrapped around the hammer and nipple after the percussion-cap is inserted to render the shell impervious to water when submerged.

Under the above arrangement many premature explosions have occurred from pieces of rock and other foreign substances falling into or dropping down from the sides of the well and upon the hammer while the shell is being lowered to its place.

The object of my invention is to so arrange the igniting apparatus that there shall be no risk of premature ignition from falling substances, and no packing required around any part of the shell; and an equally important part of my invention is my improved arrangement for distributing the flame from the cap

or cartridge throughout the entire length of the shell at practically the same instant.

In the drawings, Figure 1 represents a vertical section of my torpedo; Fig. 2, a horizontal section on line A B; and Fig. 3, a horizontal section on line C D.

a represents the cylindrical shell, made preferably of cast metal, closed at the lower end by a screw-plug, *b*, and at the upper end by a cap, *c*. The central portion of said cap is made of the conical form shown, and the shell is lowered into the well by means of a rope or wire attached to the apex of the cone *d*. Around the base of said cone two or more small holes, *e e*, are drilled through the cap, and a common pistol or rifle cartridge, *f*, is inserted into each, fitting closely thereto, as in the breech-loading rifle, so that no special packing is required around them.

When the shell is lowered to the proper depth a weight, *g*, of the peculiar form shown, is slipped over the rope or wire and allowed to fall from the top of the well. Said weight is made of such a form that it shall fit upon the cone *d* of the cap, and the lower thin edge of the weight strikes upon and ignites the cartridge or cartridges, the object of the cone *d* being to guide the lower edge of the falling weight to the cartridge.

By this arrangement of parts certainty of explosion is guaranteed, the whole apparatus is simple and cheaply made, and the cartridges *f f* are so placed as to offer no risk of premature explosion from accidental contact with foreign bodies. No packing is necessary, and the danger of wrapping a rubber tube around a hammer and nipple upon a loaded shell is avoided.

Within the shell, and communicating with each of the cartridges *f f*, I place one or more hollow perforated tubes, *h h*, corresponding in number with the number of cartridges used, extending from said cartridges to, or nearly to, the bottom of the shell. These tubes are attached to the cap *c*, and are inserted into the shell from its upper end. The cap is screwed in, the shell inverted and filled through the hole in the lower end thereof, the powder entirely surrounding, but not entering, the tubes *h h*.

When the cartridge *f* is ignited the flame

therefrom flashes through and completely fills the tube *h*, and communicates, through the perforations, with the powder around it.

I should ordinarily use two or more cartridges and tubes, and by this arrangement the flame is brought into contact with the powder in every part of the shell at practically the same instant.

Having thus described my improvements, what I claim as my specific invention, and desire to secure by Letters Patent, is—

1. The described arrangement of the cone

d, weight *g*, and cartridges *ff*, said cone serving as a guide to the descending weight, as and for the purposes set forth.

2. The hollow perforated tubes *h h*, in combination with the percussion-cartridges *ff* and loaded shell *a*, for the purpose of distributing the flame, substantially as set forth.

FREDERICK CROCKER.
